TWO-PIECE BUCKLE

Lues Reiter, Providence, R. I.

Application December 27, 1933, Serial No. 704,082

6 Claims. (Cl. 24—191)

The present invention relates to buckles for belts or straps and particularly, to the type without prongs or tongues wherein the belt or strap is clamped or gripped between the buckle parts.

5 My invention contemplates the provision of a buckle in which the parts need merely be snapped together after the passage of a belt or strap therethrough to firmly secure the belt in place, an audible click or snap apprising the user when the buckle is closed, and a similar click or snap occurring when the buckle is opened to release the belt.

10 My invention further contemplates the provision of a two-piece snap buckle which is simple and efficient in operation, adapted to be economically manufactured from sheet metal, and adapted for use with various articles such as articles of apparel as well as other goods in which adjustable buckles may be used.

15 My invention further contemplates the provision of a snap buckle having a pair of frame elements hingedly connected together at one of the ends thereof and adapted to cooperate to clamp or grip a strap between the adjacent free ends of the elements wherein the strap is securely and adjustably held.

20 My invention further contemplates the provision of buckle means to adjustably hold the free end of a strap by pinching, gripping or clamping said free end between elements wherein the gripping portions compress the strap along a substantially straight line to effectively grip the strap and to maintain it against slipping under tension or otherwise while nevertheless permitting easy adjustment of the effective length 25 thereof.

25 These and other objects and features of the invention, and the means for their attainment, will be apparent from the following detailed description, taken in connection with the accompanying drawing, which is illustrative of certain preferred embodiments of the invention, and in which,

30 Fig. 1 is a top plan view of a buckle showing a preferred embodiment of the invention in operative engagement with a belt or strap.

35 Fig. 2 is a longitudinal vertical sectional view thereof.

40 Fig. 3 is a view similar to Fig. 2 but showing the position assumed by the buckle parts immediately prior to the gripping of the strap end and just before the snap action occurs.

45 Fig. 4 is a top plan view of an alternate form of my new buckle, wherein an additional cross bar is provided to hold the free end of the belt.

50 Fig. 5 is a similar view of another modified

form of the same, wherein the additional cross bar is differently arranged.

5 Fig. 6 is a vertical section of the buckle of Fig. 5.

10 In the embodiments of the invention here illustrated, the improved buckle comprises a pair of superimposed frames 5 and 6 hingedly connected to each other. Said frames may be shaped to suitably meet specific requirements. As shown, the frames of Figs. 1 to 4 are substantially D-shaped in outline. The frame 6, however, is preferably made of less length than that of the frame 5. Said frame 5 (in Figs. 1 to 4) is provided with an end bar 7 and an opposed and preferably though not necessarily narrower end bar 8. The frame bars are integrally connected at their respective ends with the longitudinal side bar members 9 to provide the opening 10 surrounded by said bars.

15 The bar 7 of the frame 5 is preferably arched upwardly as shown and its inner edge 11 adjacent the opening 10 may be suitably rounded to obviate abrasion of the strap or belt, said edge being arranged preferably straight and extending across the frame.

20 For reasons later apparent, the plane or outer surface of the bar 7 is offset relatively to the plane of the bars 9, said bars being joined at 12 by an integral bend which is preferably concave upwardly. In the present instance, it is preferred to make the frame 5 of a material such as 25 metal of sufficient rigidity to resist distortion against a force applied between the bars 7 and 8.

25 The frame 6 is preferably made of material of a lighter gauge or thickness than that of the frame 5, and comprises the respective parallel end bars 13 and 14 and the side bars 15 integral therewith and joining the end bars to provide the opening 16.

30 The end bar 13 is preferably arched in a manner similar to the end bar 7 and its outer edge 17 is straight though it may be rounded to prevent cutting into the belt in a manner similar to the edge 11. The end bar 14 is integrally provided with a preferably cylindrical loop 18 encompassing the end bar 8 in a manner to permit free hinged relative movement of the frames. While, in the drawing, the loop 18 is shown as 35 carried by the frame 6, it may, of course, be carried by the frame 5 with entirely similar results in a manner shown, for example, in my copending application Serial No. 699,512, and in Fig. 6.

40 It will be noted that the frame 6 terminates at its free end along a line adjacent and in slight spaced relation to the offsetting bends 12 in the 45

50 55

frame 5 to permit the side bars 15 of one frame to come into contact with the side bars 9 of the other frame, and when the frames are in such contact, to permit the edge 17 of the smaller frame 5 to assume a position below the edge 11 of the larger frame.

It will be remembered that the frame 5 is preferably made rigid and non-distortable and that the frame 6 is preferably made of material of a lighter gauge, stiffened by the arch of the bar 13 and the loop integrally formed with the end bar 14. The side bars 15 of the smaller frame 6, however, are adapted to flex to any extent which may be found desirable under pressure against the edge 17, as when the frames are snapped together.

In use, the attached end of the belt or strap 19 is looped, as at 20, around the bar 14 and the doubled back portion is stitched or otherwise attached in place as at 21 against displacement. The free end 22 of the belt is passed beneath the end bar of the larger frame through the opening 10 so as to form the bight 23 around the edge 11 of said bar 14. As the smaller frame 6 is now swung downwardly toward the larger frame, the edge 17 is forced against the bight 23 of the belt, compressing it against the edge 11 and if the belt offers sufficient resistance, simultaneously causing a flexing of the side bars 15 of the smaller frame. The combined action of the compression of the belt material and the flexing of the bars 15 permits the continued downward movement of the smaller frame 6 until the bars 15 are stopped by their contact or engagement with the bars 9, in which position the edge 17 is below the edge 11. During the last part of the movement just described, that is, when the edge 17 moves from a position just above the edge 11 to a position below said edge, the sudden release of the stresses on the parts causes a highly desirable snap or click to occur, thereby apprising the user that the parts have been driven home and are locked and in proper belt-securing position. The inherent elasticity of the belt material and of the frame bars 15 tend to cause the buckle parts to retain their locked relation between the frames and only manual lifting of the smaller frame 6 can disturb said comparatively unstressed relation. Such lifting of the smaller frame again 50 stresses the buckle parts as when the edges 11 and 17 reach the same plane. Continued movement past the plane on the unlocking movement again suddenly releases the stresses on the parts to cause a snap and again to apprise the user that the buckle is unlocked. The edge 17 cannot 55 so move accidentally because of the comparatively great force necessary to stress the parts sufficiently.

It will be understood that the belt material need not be resilient to insure the snapping action above described, but that proper design of the bars 15 to give the desired flexure provides the means to retain the locked assembly of the buckle frames and the belt. Similarly, the bars 15 may be rigid and the resiliency of the belt material may provide the means to retain the above-mentioned cooperative relation. Nor need the openings 10 and 16 be large. In fact, if desired, these openings may be reduced substantially to slots of sufficient width to just permit the passage of the belt therethrough, and the frames may be otherwise solid.

That form of the invention shown in Fig. 4 is similar to that above described and shown in 75 remaining figures except that the frame 6 is pro-

vided with a bar 24 intermediate and parallel to the end bars 7 and 8 to form the openings 16a and 16b. It is intended that the free end of the belt be passed under the bar 24 to hold it against curling up or flapping about.

It will be seen that my new buckle here disclosed may be quickly and easily adjusted by unskilled persons, that it is simple, economical and efficient, that the necessity of strap-piercing elements is obviated, that the parts have no tendency to mutilate the strap, that it gives the highly desirable snap action demanded in various types of fasteners such as snap fasteners, and that it is well adapted to meet the requirements of practical use.

In that form of my invention shown in Figs. 5 and 6, the larger frame 26 is provided with an integral extension 27 in the form of a loop having a cross bar 29, the cross bar 30 between the end bars 7 and 29 being preferably integral with the remainder of the frame and replacing the end bar 8 of the other figures. The loop 28 replaces the loop 18 of the frame 6, and extends integrally from the cross bar 30, being bent around the end bar 25 of the smaller frame 6. The free end 22 of the belt is passed between the frames 26 and 6 through the slight space between the edges 11 and 17 thereof, then over the secured end 20 of the belt, which is fastened about the loop 28, and then under the end bar 29. It will be understood that the side bars of the larger frame may be offset at any desired point as 31 to permit the frames to come into proper contact and the edges 17 and 11 to properly grip the belt, and to provide the desired snap action above described.

From the foregoing, it will be seen that a simple and new snap device for the purpose mentioned has been disclosed in the preferred forms of its embodiment. However, I do not desire to limit myself to the specific construction shown, it being obvious that changes, not involving the exercise of invention, may well be made without departing from the spirit of my invention, so that I intend to claim my invention as broadly as is permitted by the state of the prior art and the scope of the appended claims.

I claim:

1. In a buckle, a pair of sheet metal frames of different lengths pivoted together at one end of the buckle, each of said frames comprising a pair of comparatively wide and thin end bars extending completely across the frames, and a pair of spaced side bars integrally joining the end bars, and offset portions on the longer frame at the side bars thereof forming recesses independent of the end bars of the longer frame for the reception of the shorter frame to permit the outer edge of an end bar of the shorter frame to pass the inner edge of the adjacent end bar of the longer frame and thereby to permit snapping engagement and disengagement of the frames with a belt passed therebetween.

2. A snap buckle comprising a pair of sheet metal frames of different lengths, each of said frames comprising a substantially D-shaped member having wide and thin end bars, and wide and thin connecting side bars, the adjacent end bars of the respective frames being pivotally connected and the other end bars being arched in a direction longitudinal of the frames and arranged in tandem relation to each other with said other end bar of the shorter frame arranged inwardly of said other end bar of the longer frame to provide a pair of separable adjacent belt-engaging edges on said respective other end bars, one of

5 said edges being the outer edge of the shorter frame and the other being the inner edge of said other end bar of the longer frame, the frames being adapted to be stressed on the insertion of a belt between said edges, the side bars of the longer frame inwardly of said other end bar being depressed to permit said edges to pass each other.

10 3. In a buckle, a pair of superimposed sheet metal frames pivotally secured together at one end, a bar integrally formed at the other end of each frame, side bars on the frames joining the end bars thereof, the outer edge of the bar of one frame being in longitudinal spaced relation to the inner edge of the other bar to provide a 15 belt-receiving space therebetween, said outer edge being arranged below the remainder of said bar of said one frame and in the plane of the side bars of said one frame, said edges, after engagement with a belt being relatively movable past each other into locked position in one direction, and being movable from locked position past 20 each other into belt-releasing position.

25 4. In a buckle, a pair of sheet metal frames of different lengths pivoted together at one end and relatively movable toward each other into locked position, a wide but thin end bar at the other end of each frame, superimposed wide but thin side bars on each frame integrally connecting the respective end bars to the respective pivoted portions, the outer edge of one end bar being in longitudinal spaced relation and below the inner edge of the other end bar, and both of said edges 30 engaging a belt passed therebetween in the locked

position of said frames, the side bars of the frame having said outer edge being superimposed upon the side bars of the other frame.

5 5. A buckle comprising a pair of superimposed sheet metal frames of different thicknesses of material and having cooperating closely adjacent continuous belt-engaging edges, one of said frames being shorter than the other and the shorter frame being of the thinner material and having comparatively narrow side bars adapted longitudinally to flex when the frame is in engaged relation with a belt inserted between said edges and thereby longitudinally stressing said frames to cause said frames to snap into and out of its locking position with an audible sound, and means extending from one of the frames and passed about part of the other frame for pivotally connecting the frames.

10 6. A buckle comprising a pair of superimposed sheet metal frames, one of said frames being shorter than the other and the shorter frame being of thinner material than the longer frame and of such little thickness as to yield under longitudinal stress put thereupon whereby forcible engagement of said frames with a belt passed therebetween causes longitudinal flexure of portions of the shorter frame out of engagement with the belt to produce a snap action and sound, and means integral with the material of one of said frames and extending therefrom about part of the other 15 frame for pivotally connecting the frames.

20 30 LUES REITER.
